United States Patent Office

Des. 223,005
Patented Feb. 22, 1972

223,005

TABLE

Donald Michael Genaro, Haworth, and Rembert Ryan
Stokes, Middletown, N.J., assignors to Bell Telephone
Laboratories, Incorporated, Murray Hill, N.J.

Filed June 15, 1970, Ser. No. 23,495

Term of patent 14 years

Int. Cl. D6—03

U.S. Cl. D33—14

FIG. 4

FIG. 1

FIG. 6

FIG. 5

FIG. 1 is a perspective view of a first embodiment of our design for a table;

FIG. 2 is a front view of the table of FIG. 1, the rear view being substantially the same;

FIG. 3 is a side view of the table of FIG. 1, the opposite side being substantially a mirror image thereof;

FIG. 4 is a perspective view of a second embodiment of our design for a table;

FIG. 5 is a front view of the table of FIG. 4, the rear view being substantially the same; and

FIG. 6 is a side view of the table of FIG. 4, the opposite side being substantially the same.

We claim:

The ornamental design for a table, substantially as shown and described.
